WINDOW CONSTRUCTION UNIT

Harold Edwards, Syracuse, and Russell B. Nelson, Onondaga, N. Y., assignors to The O. M. Edwards Company, Inc., Syracuse, N. Y., a corporation of New York

Application June 4, 1940, Serial No. 338,774

2 Claims. (Cl. 189—64)

This invention relates to window construction for railway cars, buses and the like, and has for its object, a particularly simple and economical construction by which the sash, and particularly a double sash, can be applied to car bodies of different construction, so that one standardized sash construction is readily and economically adapted to the different types of car bodies or the window openings thereof.

The invention also has for its object heat insulating the inner sash of the double sash and the adapter from the transfer of heat through the window frame or portion of the car body around the window opening and through the sash and the adapter frame to the interior surface of the sash or the car body or the adapter to avoid condensation of moisture on the inner sash, which runs down and forms pools on the window sills.

Other objects will appear throughout the specification.

The invention consists in the novel features and in the combinations and constructions hereinafter set forth and claimed.

In describing this invention, reference is had to the accompanying drawing in which like characters designate corresponding parts in all the views.

Figure 1 is a fragmentary elevation of a window unit embodying this invention.

Figure 2 is an enlarged section on line 2—2, Figure 1, the contiguous portion of the car body around the window opening being also shown.

Figure 3 is a view similar to Figure 2 illustrating the adapter for another construction of car body or different construction of car body from that shown in Figure 2.

Figure 4 is a view similar to Figures 2 and 3 illustrating a modification of the adapter shown in Figure 3.

The construction of car bodies or window openings of various makes of vehicles, as for instance, Pullman cars, Greyhound buses, etc., differ, and heretofore the manufacturer and supplier of sash equipment has been obliged to make the sash to conform to the differences in the car body constructions around the window opening.

This invention comprises means by which the manufacturer's standardized sash can be applied to the window openings of different makes of car bodies, and therefore the invention comprises a window construction unit including a sash and an adapter frame, in which the sash is mounted, the sash and the adapter frame being mountable in the window opening with the sash secured at its edge in the adapter frame as a unit there-

with, so that the manufacturer and supplier can supply one type of sash for the different car bodies together with the adapter frame for the particular car body in which the installation is to be made. As railway cars and buses, etc. are usually air-conditioned, the sash are double and stationary.

1 and 2 designate respectively the outer and inner sash, these being formed hollow and of metal. 3 designates the adapter frame, and 4 (Figure 2) designates generally one type of car body construction around the window opening; 40 (Figures 3 and 4) another type of car body.

In the form shown in Figure 2, the car body is 15 formed on the outer side with a metal sheet, plate or flange 5 opposed to the outer face of the sash 1 and a backing and weather strip 6 is interposed between the flange 5 and the confronting face of the sash 1, this strip 6 being usually of rubber.

20 The strip is so constructed as to be flexible rather than compressible. It is rendered flexible by reason of the inclined ridges or barbs 7 in the base portion thereof which flex when the sash 1 is pressed against it and also by a flexible lip 8. 25 The construction of this strip 6 per se forms no part of this invention, but constitutes the subject matter of another application.

One of the sash 1, 2, preferably the outer sash 1, is secured to the adapter 3 and the inner sash 2 is demountable or openable, it being here shown as hinged at 9 to the outer sash 1. It is secured to the outer sash 1 by quickly operable securing means designated generally 10 carried by the sash 2 and having an arm or button 11 operable 30 by a partial rotary movement into and out of interlocking engagement with the sash 1. These buttons are operable by means of screws 110 exposed on the inner face of the sash 2. The securing means 10 constitutes a unit readily applied 35 to the sash 2 and secured thereto, as by screws 12.

The glass panes 13 and 14 of the sash are seated in suitable resilient linings 15 in channels in the sash 1, 2 and the glass panes are also held 40 in position by removable glazing strips 16, one for each sash 1, 2. The glazing strips are located between the glass panes and compress against each other upon interlocking of the arms or buttons 11 with the sash 1. They tightly seal the 45 space between the glass panes against interchange of air between said space and the atmosphere inside and outside of the car body. The glazing strips are usually of rubber and are kept compressed against each other and the glass by 50 their own resiliency under compression, and by 55

spring follow-up means embodied in the securing parts 10.

The adapter frame 3 is angular in cross-section, and one flange 17 thereof, in the form shown in Figure 1, laps the inner side of the car body opposite to that on which the flange 7 is located, and the other flange 18 extends transversely of the sash 1, 2 across the edge thereof and circumferentially around the sash. One of the sash, as the outer sash, is secured at its edge to the flange 18 in any suitable manner, as by screws 19 extending edgewise into the sash 1. The adapter 3 is secured to the car body around the window opening by fastening means, as screws 20, extending through the flange 17 of the adapter frame and into any convenient part, as 21, of the car body.

A spacer or shim blocks 22 may be located between the car body 4 and the flange 18 of the adapter frame. 23 designates a heat insulating strip between the flange 18 of the adapter frame and the edge of the sash 1, and 24 a suitable cover strip for the space between the sash 1, 2 to provide a dead air space between the sash.

The weather strip 6 also acts as a heat insulator as do the glazing strips 16 to prevent the transfer of heat from the outside to the inside of the car body through the metal adapter frame and sash, and thus condensation of moisture on the inner side of the metal sash 2 and the running down of such moisture on the sill S is prevented.

In Figure 2, the adapter frame 3 is applied to the car body from the inner side of the car body. In Figures 3 and 4, it is applied to the car body from the outer side thereof.

In Figures 3 and 4, 39 designates the adapter frame, which is secured to the car body 40 by the screws 20^a, suitable insulating strip 23^a being interposed between the car body and the adapter frame 30. 22^a designates spacers or shims between the adapter frame 30 and the outer sash 1.

In the form shown in Figure 3, the adapter frame is located between a finishing sheet 25 and the car body, this sheetlapping the sash 1 with its upper edge located in a groove at 26 formed in the sealing strip 15 for the glass pane 13. A suitable heat insulating strip 27 is interposed be-

tween the sheet 25 and the face of the sash 1.

In Figure 4, a construction similar to that shown in Figure 3 is shown for a construction in which the body is not provided with a finishing sheet 25. In this form of the invention, the adapter frame 30 is formed with a bead or flange 28 covering the joint between the sash 1 and the adapter frame 30.

The sash 1, 2 are the same in any of the installations, but these standardized sash are adaptable to the various types of window openings or to the portions of the car body around the window opening by means of the adapter frame 3 or 30, so that by reason of this unit consisting of the sash and the adapter frame, a standardized sash may be economically applied to the various car body constructions; and the sash insulated from the adapter frame, the insulation not only preventing the conduction of heat or cold but also absorbing some of the vibration or weave of the car body structure and relieving the sash unit of the weaving effect.

What we claim is:

1. The combination with a car body formed with a window opening; of a window construction unit comprising opposing sash, an adapter frame mountable in the window opening from one side of the body, the car body on the opposite side having a flange opposed to one of the sash, and means for securing that sash at its edge to the adapter frame, the other sash being secured to the sash which is secured to the adapter frame.

2. The combination with a car body formed with a window opening; of a window construction unit comprising opposing sash, an adapter frame mountable in the window opening from one side of the body, the car body on the opposite side having a flange opposed to one of the sash, means for securing that sash at its edge to the adapter frame, the other sash being secured to the sash which is secured to the adapter frame, the adapter frame having an outwardly extending flange lapsing the body around the window opening, and means for securing the last flange to the body.
